UNITED STATES PATENT OFFICE.

BENAIAH FITTS, OF WORCESTER, MASSACHUSETTS, ASSIGNOR TO THE UNION WATER METER COMPANY, OF SAME PLACE.

WATER-METER.

SPECIFICATION forming part of Letters Patent No. 299,213, dated May 27, 1884.

Application filed August 25, 1881. (Model.)

To all whom it may concern:

Be it known that I, BENAIAH FITTS, of Worcester, in the county of Worcester and State of Massachusetts, have invented certain 5 new and useful Improvements in Water-Meters; and I declare the following to be a description of my said invention sufficiently full, clear, and exact to enable others skilled in the art to which it appertains to make and use the 10 same, reference being had to the accompanying drawings, which form a part of this specification.

This invention has especial reference to that 15 class of meters known as the "Worthington Meter," and described in Letters Patent No. 13,320, wherein two reciprocating pistons and slide-valves are employed, one piston acting directly to operate the valve governing the 20 flow of water to the other piston, and vice versa. These meters as heretofore constructed, although quite satisfactory in their general 25 operation, are defective in the arrangement of their ports or valve-passages to and from the cylinders, these being a source of frequent derangement and annoyance, since in practice the 30 passages are liable to become filled or clogged with sediment and dirt, and when so clogged their form and arrangement are such that it is inquiring in some localities much time, labor, and trouble to keep the meter in proper running condition.

The object of my present invention is to obviate this defect and to provide the meter with 35 ports and passages which will permit free flow of water, while they are not liable to become clogged, and are conveniently accessible when desired. These objects I attain by the mechanism constructed as shown and herein 40 scribed.

In the drawings, Figure 1 is a longitudinal section of a meter, (at the position indicated by line $w w$ in Fig. 4,) illustrating the nature of my invention. Fig. 2 is a transverse section of the cylinder at line $x x$ of Fig. 1. Fig. 45 3 is a transverse section of the cylinder at line $y y$ of Fig. 1. Fig. 4 is a plan view of the valve-seat plate.

In reference, A and A' denote the two cylinders, respectively provided with pistons B 50 B', fitted to move back and forth with a reciprocating action.

C indicates the valve-seat plate, secured to the bottom of the cylinders, and provided with guideways c for the slide-valves D, which are 55 arranged to move over their seats and ports by engagement with the pistons B B', the central portion of which is recessed, leaving shoulders b, which engage the projections d on the valve D.

E E' indicate the passages leading from the valve-ports e e' to the cylinder A', and I I' indicate the passages leading from the ports i i' to the other cylinder, A. These several passages are all made straight and direct in the 65 valve-seat plate, as shown, and are then carried up into the cylinders in the peculiar manner illustrated—i. e., the two passages E' and I' being made to take a twisting course and to pass each other within the triangular piece between the cylinders, said passages being separated from each other by a spiral or winding partition, which forms a part of the main dividing-partition between the cylinders. The 70 passages communicate with the enlarged end 75 chambers of the cylinders just beyond the finished piston-bearing surfaces a a, as illustrated. The said passages can be made by properly-adjusted cores when casting the cylinders.

The general action of the pistons and valves, 80 as well as the registering mechanism, (not shown herein,) being substantially the same as in the ordinary meters of this class, need not be herein more definitely described.

The advantages of my improvements are 85 simplicity in the construction and facility of manufacture, adaptation of passages for giving a free flow of water, and non-liability to become clogged by sediment; also, the convenience of access to the interior of the valve-seat plate 90 for cleaning out said passages.

What I claim as of my invention, and desire to secure by Letters Patent, is—

The combination of the cylinders A A', 95 having internal bearing-surfaces, a a, said cylinders being separated below by a triangular-

shaped space, the pistons B B', provided with shoulders *b b*, the removable valve-seat plate C, having guideways *c c* and ports *e e' i i'*, and the valves D D', provided with projections *d*,
5 the valve-seat ports being connected with the ends of the cylinders by straight parallel passages E I, located in the ends of the valve-seat plate, and spirally-crossed passages E' I', lo-

cated in the triangular space beneath the cylinders, substantially as shown and described. 10

Witness my hand this 22d day of August, A. D. 1881.

BENAIAH FITTS.
